UNITED STATES PATENT OFFICE

WILLIAM I. MACOMBER, OF PROVIDENCE, RHODE ISLAND.

SELF-CLOSING BRACELET.

No. 827,164.

Specification of Letters Patent.

Patented July 31, 1906.

Application filed March 13, 1906. Serial No. 305,881.

To all whom it may concern:

Be it known that I, WILLIAM I. MACOMBER, a citizen of the United States, residing at Providence, in the State of Rhode Island, 5 have invented a new and useful Improvement in Self-Closing Bracelets, of which the following is a specification.

My invention consists in the improved construction of the spring-actuated joint of 10 the bracelet, as hereinafter set forth.

In the accompanying drawings, Figure 1 represents a side view of a hollow wire bracelet to which my improvement is applied. Fig. 2 represents an enlarged longitudinal section of the closed spring-actuated joint, taken in the plane of the arms of the bracelet. Fig. 3 represents a longitudinal section of the same, taken in the line 3 3 of Fig. 2. Fig. 4 represents a section, as in Fig. 2, with 15 the arms of the bracelet opened. Fig. 5 represents a transverse section taken in the line 5 5 of Fig. 3. Fig. 6 represents a side view of the sliding yoke, which serves to hold the actuating-spring of the bracelet- 20 joint. Fig. 7 represents an edge view of the same. Fig. 8 represents a side view of the actuating-spring. Fig. 9 represents an edge view of the piece of grooved stock from which the joint-pieces are to be formed. Fig. 10 represents a transverse section of the 25 same. Fig. 11 represents an edge view showing a properly-bent piece of stock of sufficient length to make both joint-pieces of a bracelet. Fig. 12 represents the same edge view, showing the portions to be removed 30 from the blank shown in Fig. 11 preparatory to the separation of the joint-pieces. Fig. 13 represents the completely-formed joint-pieces with their inner ends abutting each 35 other.

In the drawings, A represents one of the hollow arms of the bracelet, and B the other hollow arm, the said bracelet being provided with the improved self-closing joint C. 40 The joint-piece D is soldered firmly in the cavity of the arm A of the bracelet and is constructed as shown in Fig. 13, being provided with the perforation a for the pivot b and the cut-away recess c, which is adapted 45 to receive the projecting lip d of the opposite joint-piece E, the said lip d serving to close the inner side of the joint C when the arms A and B of the bracelet are thrown open, as 50 shown in Fig. 4. To the joint-piece D is pivoted the yoke F, the curved arms e e of 55 which are adapted to slide loosely in the

curved grooves f f, formed in the opposite edges of the joint-piece E. The joint-piece E is provided with the cavity g, which is adapted to receive and hold the actuating- 60 spring G, the outer end of the said spring being held in contact with the cross-bar h of the said yoke F, so that the expansion of the said spring G will serve to draw the inner ends of the joint-pieces D and E forcibly together, and thus cause the closing of the arms of the bracelet. When the arms of the bracelet are being opened, as shown in Fig. 4, the projecting end i of the joint-piece D will act as a lever to cause a drawing action upon 65 the yoke F and the compression of the spring G, the corner j constituting the fulcrum for the turning movement.

Heretofore in self-closing bracelets of this class the turning-f fulcrum has been located at 70 the abutting ends k k of the hollow arms of the bracelet, with resulting wear and injury; but in my invention the wear does not come upon the said hollow arms, but upon the joint-pieces D and E, which are soldered in 75 the cavities of the said arms in such a position that the abutting ends k k of the hollow arms A and B lie in about the plane of the center of the pivot-pin b, as shown in Figs. 2 and 3, whereby when the arms A and B are 80 being opened the outer edge of the arm A will be drawn inward, as shown in Fig. 4. The projecting end i of the joint-piece D bears against the face o of the joint-piece E, which face is back of the plane of the end of 85 the hollow arm B.

In the manufacture of the joint-pieces D and E, I first form a bar H of suitable cross-section, having the opposite longitudinal grooves e e, as shown in Figs. 9 and 10, and then bend the said bar in longitudinally- 90 curved form, as shown in Fig. 11. The stock is then cut away at m and n to form the joint-pieces.

I claim as my invention—

1. In a self-closing bracelet, the combination of a joint-piece provided with opposite grooves, the yoke held in the said grooves, and the actuating-spring, with the opposite joint-piece, pivoted to the yoke and adapted 100 to fulcrum upon the end of the grooved joint-piece when the arms of the bracelet are being opened.

2. In a self-closing bracelet, the combination of the hollow arm of the bracelet the 105 joint-piece provided with the grooves, and secured in the said hollow arm which pro-

jects beyond the end of the said joint-piece, and the opposite joint-piece projecting beyond the end of the hollow arm to which it is secured, with the yoke-piece pivoted to the 5 said projecting joint-piece, and held in the grooves of the opposite joint-piece, and the actuating-spring held in the said yoke.

3. In a self-closing bracelet, the combination of the hollow arm of the bracelet the 10 joint-piece provided with the grooves and the projecting lip, and secured in the said hollow arm which projects beyond the end of the said joint-piece, and the opposite joint-piece

provided with a recess at its inner side adapted to receive the said projecting lip, and projecting beyond the end of the hollow arm to which it is secured, with the yoke-piece pivoted to the said projecting joint-piece, and held in the grooves of the opposite joint-piece, and the actuating-spring held in the 15 20 said yoke.

WILLIAM I. MACOMBER.
